Primary Examiner — Cathron C Brooks*(74) Attorney, Agent, or Firm* — Ward and Smith, P.A.;
Ryan K. Simmons(57) **CLAIM**

The ornamental design for an infant bed, as shown and described.

DESCRIPTION

FIG. 1 is a perspective view of the infant bed showing a new design;

FIG. 2 is a right side view thereof;

FIG. 3 is a left side view thereof;

FIG. 4 is a back view thereof;

FIG. 5 is a front view thereof;

FIG. 6 is a top view thereof; and,

FIG. 7 is a bottom view thereof.

The dashed lines illustrate portions of the infant bed that form no part of the claimed design.
